UNITED STATES PATENT OFFICE.

FRANK CORNING BROWN, OF LOVELAND, COLORADO, ASSIGNOR OF ONE-HALF TO ORLANDO D. SHIELDS, OF LARIMER COUNTY, COLORADO.

LEVELING OR GRADING INSTRUMENT.

SPECIFICATION forming part of Letters Patent No. 630,856, dated August 15, 1899.

Application filed March 16, 1898. Serial No. 673,915. (No model.)

To all whom it may concern:

Be it known that I, FRANK CORNING BROWN, a citizen of the United States, residing at Loveland, in the county of Larimer and State of Colorado, have invented a new and useful 5 Leveling or Grading Instrument, of which the following is a specification.

My invention relates to improvements in leveling or grading instruments in which are 10 a tube with a sphere on top and point on its lower end, provided with a connection for a hose near the ground-line, a tube with a gage-glass, means for making a water joint on said glass, provided with a connection for 15 a hose near the ground, a graduated staff and means to adjust the tube (with the glass) and secure it to said staff, and a hose-pipe connecting the two tubes, said hose and tubes to be filled with water, making an instrument 20 especially adapted for the use of the farmer in grading his ditches for irrigating. It is simple in construction and operation and is accurate. I attain these objects by the mechanism illustrated in the accompanying drawing, which represents the same in side elevation, some of the parts being shown in side 25 elevation and others broken away.

The line 1 represents the ground, 2 the point of the plain tube, 3 the connecting-coupling, 30 4 the tube, and 5 the sphere provided with a screw-threaded top to receive the valve-stem 6, and a valve-seat at the point where it is connected to the tube. An opening 11 is provided in the sphere 5 for an air-vent. 8 is the hose-coupling and the gage-glass coupling of the 35 adjustable tube; 9, the glass gage, provided with the gage-line 9^a; 10, the sphere having a tube on its lower end to receive the gage-glass and provided with a clamp to receive the staff 15. The lower end of said tube is 40 provided with a screw-thread to receive the tube 8.

12 and 13 are rubber packing-rings.

7 is a hose-pipe connecting the tubes 4 and 45 8, said tubes being about four feet high.

The object of the valve 6 is to keep the air from entering the tube when the instrument is in a horizontal position.

The sphere or bulb 5 being of glass permits 50 easy comparison of the level of the water rising therein with that in the gage-tube 9. Each

of the spheres or bulbs 5 and 10 constitutes a convenient means of admitting water to the tube and of opening and closing the air-inlet and the outlet from said bulb to the tube. 55 The screw-threaded valve 6 is also a stopper for the bulb in each instance. When it is unscrewed and removed, water may be supplied through the inlet thus left open. When it is screwed quite home, it closes simultaneously the air-inlet 11 and the outlet of the said bulb to the connecting-tube. This allows the atmospheric pressure to reach the water, and in the case of the lower bulb 5 also allows the access of the water to the said bulb. 65

The operation is as follows: The tubes 4 and 8 are filled with water, as shown, after the hose 7 has been connected. Said hose may be one hundred or two hundred feet, as the operator may require. The valve 6 of 70 each sphere is released, the tube 4 is forced in the ground, and the level is taken on the glass gage. The operator wishing to have a grade of three inches in one hundred feet will lower his gage-tube so many inches on his 75 staff and plow his ditch until the water comes to the line on the glass.

It will be evident that certain changes may be made in the construction of my instrument without departing from the scope of the invention. 80 Hence I do not limit myself to the exact details of construction and arrangement of parts herein shown and described.

Having described my invention, what I do claim as new, and desire to secure by Letters 85 Patent, is—

1. In a grading instrument, the combination of a relatively-fixed hollow part 5 having an outlet-opening and valve-seat in its bottom, and an air-inlet 11 and water-inlet arranged side by side in its top, with a valve 6 which is screw-threaded to engage the corresponding threaded wall of the said water-inlet, and provided with a head of sufficient area to cover the said air-inlet, the said valve 95 being of sufficient length to extend diametrically through the said hollow part from the top to the bottom thereof and fit into the said valve-seat and outlet in order that the air-inlet and the said outlet may be simultaneously closed or simultaneously opened by the same device, another hollow part 10 substan- 100

- tially identical in construction with the said part 5 and provided with a similar valve, means for supporting the said hollow part 5 in a fixed position, means for supporting and 5 vertically adjusting the said part 10, and tubular connections between the said parts 5 and 10, substantially as set forth.
2. In a grading instrument the combination of a hollow part 10 having an outlet and 10 valve-seat in its bottom and a water-inlet and air-inlet arranged side by side in its top, with a valve which is screwed into the said water-inlet and provided with a head adapted to close and open the said air-inlet while the said 15 valve, extending down through the said hollow part simultaneously opens or closes the said outlet in the bottom thereof, means for supporting and vertically adjusting the said part 10, a similar relatively-fixed hollow part 20 5 provided with water-inlet, air-inlet, outlet and valve as aforesaid, the tubular posts 4 and 8 for supporting the said hollow parts,

and the tube 7 connecting the said posts for the purpose of completing communication between the said hollow parts, substantially as 25 set forth.

3. A grading instrument provided with a hollow part having in its top an air-inlet and a proximate water-inlet with screw-threaded wall, and in its bottom an outlet and surrounding valve-seat, a screw-threaded valve turning in said water-inlet, extending through the said hollow part and adapted to open the air-inlet and the outlet simultaneously or close them simultaneously at will, means for vertically adjusting the said hollow part, a tubular conduit extending therefrom, and an elevated relatively-fixed hollow part at the other end of the said conduit, substantially as set forth.

FRANK CORNING BROWN.
